[57] **CLAIM**

The ornamental design for a walkie talkie, as shown and described.

DESCRIPTION

FIG. 1 is a perspective view of a walkie talkie showing my new design;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof;

FIG. 8 is a perspective view of a second embodiment of my new design;

FIG. 9 is a front view thereof;

FIG. 10 is a left side view thereof;

FIG. 11 is a right side view thereof;

FIG. 12 is a rear view thereof;

FIG. 13 is a top view thereof; and,

FIG. 14 is a bottom view thereof.

This application includes two embodiments. FIGS. 1-7 show all views of the first embodiment of the design, and FIGS. 9-14 show all views of the second embodiment of the design.
